UNITED STATES PATENT OFFICE.

ISAAC SHERCK, OF FREMONT, OHIO, ASSIGNOR TO HIMSELF, GEORGE E. RAYMOND, OF SAME PLACE, AND WM. F. JOBBINS, OF NEW YORK, N. Y.

GRAIN-SEPARATOR.

SPECIFICATION forming part of Letters Patent No. 237,453, dated February 8, 1881.

Application filed May 5, 1880. (No model.)

To all whom it may concern:

Be it known that I, ISAAC SHERCK, of Fremont, in the county of Sandusky and State of Ohio, have invented certain new and useful 5 Improvements in Grain-Separators; and I do hereby declare the following to be a full, clear, and exact description of the invention, such as will enable others skilled in the art to which it pertains to make and use it, reference being 10 had to the accompanying drawings, which form part of this specification.

My invention relates to an improvement in grain-separators, the object being to combine with the shoe and riddles a fan of such construction that the blast of air may be directed against the riddle at any desired angle, in order to produce the most effective results in separating the chaff and refuse material from the grain; and with this end in view my invention consists in certain details of construction and combinations of parts, as will hereininafter be described, and pointed out in the claims.

In the accompanying drawings, Figures 1 and 2 are views in side elevation of that portion of the frame of a separator inclosing the fan, oscillating shoe, and riddle. Fig. 3 is a view in side elevation of one side of the casing, the fan having been removed therefrom. Fig. 4 is a plan view of the fan-casing and oscillating shoe. Fig. 5 is an end view of the fan-casing removed from the separator. Fig. 6 is a view in perspective of the opposite end of the fan-casing. Fig. 7 is a detached view of the fan. Fig. 8 is a longitudinal section of the fan-casing and plan view of the fan located therein.

A A' are the sides of the separator-frame. B is a shoe having a discharge-spout, C, attached to the outer end. The outer end of the shoe is suspended by links D, while the opposite end is connected with the crank-shaft E, so that as the latter revolves an oscillating motion will be imparted to the shoe. Riddles 45 of any desired construction are placed in the shoe and adapted to be moved therewith.

F is a fan-casing having an open end, G. The opposite end of the casing is provided with a ring, H, and a cross-bar, I, the latter 50 serving as a bearing for one end of the fan-

shaft J, the opposite end of which is journaled in the cross-bar K in the casing. The open end G of the fan-casing fits over and is supported upon an annular flange, L, formed upon or attached to the inner side of the separator-frame. 55

M is the air-eduction opening of the fan-casing, an outwardly-projecting flange, N, being formed on the fan-casing on the upper side of said eduction-passage, while the casing 60 below said eduction passage or opening is outwardly flaring from the point a to b. The side A of the separator casing or frame is provided with the slots c d, to allow of the insertion of the projecting portions N and O of the fan-casing. After the fan-casing has been inserted between the sides A A' and the open end of the fan-casing forced upon the annular flange L, the casing is then rotated to bring the air-eduction opening at the proper point 70 to deliver the blast at the desired angle upon the riddle. A plate, P, is secured to the side A of the separator-frame by means of screws p p, said plate being provided with the arc-shaped slots Q Q', through which are inserted 75 the screws R R', the latter engaging the ring H, attached to one end of the fan-casing. By loosening the screws R R' the fan-casing may be turned forward or backward a distance 80 equal to the length of the arc-shaped slots and secured in any desired adjustment by tightening the screws R R'. 75

To the fan-shaft J is secured an arm, S, to the opposite end of which are attached the fans T, each of which is provided with outwardly-flaring ends U, which project outside the sides of the separator and serve to draw the air into the fan-casing. The flaring ends of the fans serve to materially increase the capacity of the fan-blower without increasing the size 90 of the fan-casing. 85

It is often desirable to change the direction of the air-blast to cause it to strike the riddle at a certain angle, or to strike the riddle at a certain point in its length. This adjustment 95 is desirable, sometimes, owing to the particular adjustment of the shoe or riddle, and sometimes it is necessary to change the direction of the blast to insure perfect results in the treatment of different kinds or different qualities 100

- of grain. By simply rotating the fan-casing the blast of air may be directed against any portion of the riddle. The outwardly-flaring portion of the lower portion of the fan-casing allows the air to be forced outwardly from the casing in right lines, or, in other words, the fan-casing does not operate to break up and deflect the blast, as is the case in most forms of fan-blowers.
10. When it is desired to remove the fan for repairs or inspection it may be readily done by simply removing the plate P and drawing out the fan-casing and fan inclosed therein.
- If desired, I may suspend a float over the oscillating shoe by attaching any suitable blade, S', to a rock-shaft, S², and to the outer end of the shaft secure a pointer, T, the end of which is located over a graduated index, T', the purpose of the float being to correctly indicate the force of the blast employed at any given time. To the hand or pointer T may be attached a sliding weight, V, which may be adjusted toward or from the end of the hand, in order to regulate the resistance of the float to the blast.
15. My invention is also valuable in middlings-purifiers, and when used in such machines the air-education may be subdivided into any desired number of separate passages, thereby dividing the main blast of air into any desired number of separate blasts, which may be directed against different portions of the screen. The open end of the casing may have a band attached thereto to strengthen the same.
20. It is evident that slight changes in the construction and relative arrangement of parts might be resorted to without departing from the spirit of my invention, and hence I would
- 25.

have it understood that I do not limit myself to the exact construction and arrangement of parts shown and described; but,

Having fully described my invention, what I claim as new, and desire to secure by Letters Patent, is—

1. The combination, with the fan-casing, of a plate secured to the casing of the machine and provided with arc-shaped slots, and set-screws inserted through said slots and connected with a ring on one end of the fan-casing, substantially as set forth.

2. The combination, with the casing of the machine, having an annular flange on its inner side and a shaft-bearing attached to the casing of the machine, of a fan-casing having a shaft-bearing secured to one end thereof, and its other end open and adapted to fit upon said annular flange, substantially as set forth.

3. An axially-adjustable fan-casing, in combination with a fan mounted on a shaft, one end of which is journaled in a bearing connected with the fan-casing and its opposite end in a bearing disconnected therefrom, substantially as set forth.

4. The combination, with a riddle and a fan adapted to supply a blast of air to the under side of the riddle, of a float located beneath the riddle and attached to a rock-shaft, a pointer connected with said rock-shaft and an index-plate, and an adjustable weight attached to the pointer, substantially as set forth.

In testimony that I claim the foregoing I have hereunto set my hand.

ISAAC SHERCK.
